(57) **CLAIM**

The ornamental design for a mirror, as shown and described.

DESCRIPTION

FIG. 1 is front elevation view showing my new design.

FIG. 2 is a left side elevation view of the mirror of FIG. 1, the right side elevation view being a mirror-image.

FIG. 3 is a bottom end view of the mirror of FIG. 1, the top end view being identical.

FIG. 4 is a rear elevation view of the mirror of FIG. 1; and, FIG. 5 is a cross-sectional view taken along line 5—5 in FIG. 1, to clarify the configuration of the exterior surface of the mirror.

The portions of the drawings appearing in broken lines are for environment only and do not form a part of the claimed design.
